(57) **CLAIM**

The ornamental design for a modular cradle, as shown and described.

DESCRIPTION

FIG. 1 is a front, top, right perspective view of a modular cradle according to the design.

FIG. 2 is a rear, bottom, left perspective view of the cradle of FIG. 1.

FIG. 3 is a front view of the cradle of FIG. 1.

FIG. 4 is a back view of the cradle of FIG. 1.

FIG. 5 is a first side view of the cradle of FIG. 1.

FIG. 6 is a second side view of the cradle of FIG. 1.

FIG. 7 is a top view of the cradle of FIG. 1; and,

FIG. 8 is a bottom view of the cradle of FIG. 1.

The broken line portions of the drawing figures are included to show portions of the article or environment that are not part of the claimed design.

1 Claim, 4 Drawing Sheets
